UNITED STATES PATENT OFFICE.

JOHN R. HOFFMAN, OF PHILADELPHIA, PENNSYLVANIA.

MUSIC-ROLL.

1,296,392.

Specification of Letters Patent.

Patented Mar. 4, 1919.

Application filed July 20, 1918. Serial No. 245,872.

To all whom it may concern:

Be it known that I, JOHN R. HOFFMAN, a citizen of the United States, residing at Philadelphia, in the county of Philadelphia and State of Pennsylvania, have invented 5 new and useful Improvements in Music-Rolls, of which the following is a specification.

The object of the invention is to provide a 10 music feed roll for player pianos to receive the record strip or sheet from the record roll, said feed roll being provided with means for engaging the end of the record strip or sheet independently of the ring 15 with which said strips or sheets are ordinarily provided, so that in the event that the ring or similar means should become detached, as frequently occurs, the engagement of the strip or sheet may be effected 20 and the operation of the mechanism proceed as under normal or ordinary conditions.

It is a further object of the invention to 25 provide means for securing the end of the record strip or sheet to the music feed roll which will be closed or moved to engaging 30 position with relation to said strip or sheet automatically or by reason of the driving of the feed roll by the mechanism of the player, and will be maintained in such engaging 35 position throughout the operation of the mechanism, without attention on the part of the operator, but which will at the end of the operation, upon the re-rolling of the record strip be freely detached or disengaged 40 from the record strip or sheet without possibility of injury thereto.

Further objects and advantages will appear hereinafter, it being understood that 45 changes in form, proportion and details particularly in adapting the mechanism to various types of players and player pianos may be resorted to within the scope of the appended claims without departing from the spirit of the invention.

50 In the drawing:

Figure 1 is a view of a feed roll provided with a record strip or sheet engaging device constructed in accordance with the invention as seen in a player-piano of the ordinary type.

Fig. 2 is a detail side view of the feed roll detached from the piano player.

Fig. 3 is a longitudinal sectional view of the central portion of the feed roll showing 55 the clamp and operating means in detail.

Fig. 4 is a transverse sectional view on

the plane indicated by the line 4-4 of Fig. 2.

Fig. 5 is a detail view of the clamp member detached.

Fig. 6 is a similar view of one of the 60 crank arms by means of which motion is communicated from the feed roll spindle to the clamp member.

Fig. 7 is a detail section to show the 65 temporary roll restraining device.

Essentially the feed roll embodying the invention includes a spindle 10 and a drum 11 loosely mounted upon the spindle and having a central portion 12 which may consist of a metallic cylindrical casing corresponding in general outline with the body portion of the roll or drum and connected with said body portion by pins 13. The intermediate portion of the drum may be 70 provided with the usual hook 14 for engagement with the terminal ring on the record strip or sheet and designed and adapted to be used in the ordinary way.

Carried by the drum and mounted in the 75 intermediate portion 12 thereof is a clamp member 15 consisting of a jaw or bar 16 roughened or milled on its underside as shown in the detail Fig. 5 and arms 17 which are pivotally connected with crank 80 arms 18 secured fixedly to the spindle 10 whereby when motion is applied by the driving mechanism of the player to the said spindle, motion is communicated through the crank arms 18 to the clamp and thence 85 to the drum of the roll to impart winding movement thereto to feed the record strip or sheet. The tapered end portion of the strip or sheet is adapted to be inserted between the shell of the drum and said bar or jaw of 90 the clamp member, a slight depression or groove 19 being provided in the shell to avoid projection of said bar or jaw of the clamp beyond the surface of the drum. In operating the device the insertion of the end 95 of the strip or sheet beneath the bar or jaw of the clamp should be followed by a temporary holding of the latter in its engaging position by the finger of the hand of the operator until forward motion is applied by 100 the driving mechanism of the player to the spindle, and obviously as soon as this motion has been started the action of the 105 spindle in communicating motion to the drum through the clamp will hold the latter in its engaging position, and this relation of the parts will be maintained as long

as the driving operation of the feed roll continues. On the rewinding of the record strip or sheet, causing a reverse rotary movement of the feed roll which runs freely when the rewinding mechanism of the player has been thrown into operation, the pressure upon the clamp member will be relieved, so that when the end of the strip or sheet is reached it will slip freely from under the clamp bar or jaw without liability of injury to the parts.

The crank arms 18 may be secured rigidly to the spindle 10 by means of transverse keys 19, or any equivalent thereof, the arms 17 of 15 the clamp member extending through suitable openings 20 in the drum or shell formed by the intermediate portion of the roll and the spindle beyond the end of the drum may be provided with a transverse perforation 20 or drill hole 21 for the attachment of the feed gear if the latter is disposed exteriorly of the casing, but obviously this is a detail having nothing in particular to do with the present invention and will depend upon the 25 type of player in connection with which the invention is used. The main feature of the construction is the arrangement of parts whereby the rotary motion of the feed roll is communicated from the spindle to the drum through the intermediate agency of the 30 clamping means which serve to engage the extremity of the record strip or sheet and maintain the latter frictionally in relation to the feed roll during the forward movement 35 of the record strip while permitting the free disengagement of said strip from the feed roll upon the re-rolling or re-winding of the record.

This may be accomplished by the finger of 40 the operator, or by means of a lever 21, pivoted upon a bracket 22 at the back of the roll box, a beveled or cam projection 23 being arranged on the end of the roll 11 in the path of which said lever may be arranged by pressure, laterally, upon a finger piece 25 on the 45 lever. As the rotation of the roll starts the lever will be pressed laterally by the cam to remove it from the path of the projection in subsequent rotations.

50 The tightening of the clamp in starting the operation after inserting the end of the sheet under the clamp bar or jaw may be effected by slightly restraining or retarding the movement of the feed roll.

55 Having described the invention I claim:—

1. The combination with a music feed roll for piano players and driving means therefor, of a clamp for engagement with the record sheet, and means connecting said clamp 60 with said driving means to operate the clamp and hold the same in clamping position.
2. The combination with a music feed roll for piano players and driving means therefor, of a clamp carried by said feed roll, and

capable of movement into engagement with the record sheet, and means connecting said clamp with said driving means to operate the clamp and hold the same in clamping position.

3. A music feed roll for piano players having revoluble relatively movable driving and driven members, and a clamp member carried by the latter and connected with the former for movement relative to the latter 75 to engage the end of a record strip.

4. A music feed roll for piano players having a driving spindle and a drum for receiving revoluble movement therefrom, and capable of a limited independent movement, 80 and a clamp member carried by and arranged in movable coöperative relation with the drum to engage the end of a record strip, and connected with the spindle for movement into said clamping relation.

5. A music feed roll for piano players having independently revoluble members consisting of a spindle and a drum, a clamp member movably mounted upon the drum for coöperation with the surface thereof to 90 engage the ends of a record strip, and connections between the clamp member and said spindle by which revoluble movement is communicated from the latter to the drum and the clamp member is movable into 95 clamping position.

6. A music feed roll for player pianos having a spindle for receiving roll driving motion, a drum for receiving motion from said spindle and mounted thereon for independent movement, a music sheet clamp having an exposed bar or jaw for engagement with the end of a record strip or sheet, said clamp member having arms extending inwardly from the bar or jaw, and crank arms connected with said spindle and with the arms of the clamp member for communicating motion to the latter and therethrough to the drum.

7. A music feed roll for player pianos having a spindle adapted to receive driving revoluble movement, a drum loosely mounted upon said spindle and having an intermediate hollow member forming a casting, a clamp member having an exterior bar or jaw extending longitudinally of and arranged in a groove or counter-sunk portion of the intermediate member of the drum, said clamp member having arms extending into the interior of said intermediate member and crank arms secured to the spindle and connected with the arms of the clamp member for moving the bar or jaw of the latter into sheet engaging relation with the surface of the drum.

8. A music feed roll for player pianos having a spindle, a drum to receive motion from the spindle, a clamp mounted for radial sheet engaging movement on the drum and connected to the spindle to convey ro- 130

tary motion from the spindle to the drum and drum restraining means including a cam on the end of the drum, and a lever pivotally mounted for swinging movement into the path of the cam for holding the drum during the initial movement of the spindle and the coincident engaging movement of the clamp.

9. The combination with a music feed roll

for piano players and driving means therefor, of a clamp carried by said roll and movable radially of said roll for engagement with the record sheet, and means connecting said clamp with said driving means to operate the clamp and hold the same in clamping position.

In testimony whereof I affix my signature.

JOHN R. HOFFMAN.
